SHOE HEEL

William W. Brooks, New York, N. Y.

Application March 11, 1946, Serial No. 653,594

14 Claims. (Cl. 36—35)

1
This invention relates to improvements in shoes and more particularly to heels and heel attachments thereto.

One of the objects of this invention is to provide a simple, efficient and inexpensive heel lamination for the purpose of building into the heel shock-absorbing qualities as well as tread resiliency which will be effective to impart to the steps taken by the wearer of such shoe a springiness and traction comfort which would not exist otherwise.

Another object thereof is to provide a shoe heel with an attachment thereto which provides comfort in walking, which absorbs all shocks imposed on the wearer's foot in walking, and which definitely imparts to the shoe better traction qualities due to equalized resiliency and counterbalanced heft.

A further object thereof is to provide, in a device of the kind described, a series of rubber semispherical tread elements upon which pressure is imposed by the wearer of the shoe by making contact with the heel proper, said semispherical tread elements being formed with radially disposed fins with intervening recesses to increase the effectiveness of the same for better traction purpose.

A final object thereof is to provide a resilient mounting to the under surface of the shoe heel so shaped and arranged and so operating as not only to enhance better traction on the part of the shoe wearer but also to effectually absorb all shocks and cushion all impacts occasioned by the prolonged walking or standing of the shoe wearer, whilst improving upon his posture in so doing.

With the above and other objects in view, my invention consists in the combination, arrangement and details of construction disclosed in the drawings, and then more particularly pointed out in the appended claims.

In the drawings, wherein similar reference characters designate similar parts throughout the respective views,

Figure 1 is a fragmental elevation of a shoe showing one form of my invention attached thereto.

Figure 2 is a bottom plan view of Figure 1.

Figure 3 is a top plan view of the heel lamination proper.

Figure 4 is a sectional detail view of a heel and lamination attached thereto, in which a semispherical tread element is shown encased in a metal liner.

Figure 5 is a side elevation of said liner.

Figure 6 is a bottom plan view of the liner,

2

Figure 7 is a fragmental elevation of a shoe showing another form of my invention attached to the heel thereof.

Figure 8 is a bottom plan view of the lamination shown in Figure 7.

Figure 9 is a longitudinal sectional view of the heel lamination attached thereto, in one form,

Figure 10 is a side elevational of a semispherical rubber cushion.

Figure 11 is a side elevation of a semispherical rubber tread element cooperating with the part shown in Figure 10, and

Figure 12 is a plan view of a washer.

15 In the drawings, which are merely illustrative of my invention, I disclose the parts of my invention. The shoe is broadly designated A, having the leather bottom sole B to which is attached the usual heel portion 10. The heel portion 10 will be made somewhat thinner than usual because it will have in surmounted relation in contact with its under surface a lamination 12; the heel has the usual front and concave edge 11 and the lamination 12, being shaped to the same outline as the heel also has the same concave recess 13, which registers with recess 11, as shown in Figure 1.

20 In one form of my invention, illustrated in Figures 1 and 2 I show the upper surface of the lamination 12 formed with a counterseat 14 shaped similarly to that of the lamination so that there may be snugly seated therein a metal plate 15, flush with its upper surface, which metal plate will contact the under surface of the leather heel 10 at the same time other parts of the lamination do. As a means of attaching the lamination to the heel I take elongated nails 25 and drive them home through lamination 12, metal plate 15, shoe heel 10 and sole B of the shoe. The heads 27 of 25 the nails are countersunk into the lamination 12 by projecting into counterseats 24 found therein while the nails enter holes 25 therein.

25 The lamination may be composed of any suitable material known in the shoemaking art, according to the wearing sturdiness required, preferably not rubber. The heel, before it is secured upon the shoe proper is formed with a centrally disposed series of semispherical cavities 18 such that their largest diameters open out from the under side thereof, remote from the shoe upper. The lamination 12 is also formed with a series of semi-spherical openings whose largest diameters 22 open out of the upper surface thereof and whose lesser diameters 23 open out from 30 the under surface thereof, as fully disclosed in 35 40 45 50 55

Figure 9. An annular recess *c* is formed between the wall of each cavity and the adjacent surface of the lamination, the inner planes of which are rounded. If desired rubber or plastic material may be poured into these recesses *c* to vulcanize or otherwise bind the rubber balls now to be described. The lamination *12* will be attached to the heel by similar means, being preferably cemented thereto where the structure is provided shown in Figure 1, but being nailed thereto where the structure is provided shown in Figure 7. For the latter purpose, as already explained and shown in Figure 9 the lamination *12* is formed marginally thereof with a series of cylindrical tiny sockets *24* opening out from the under surface thereof, which sockets communicate with holes *25* which opens out of the upper surface of the lamination and communicate with the large area counterseat *14* therein also on its upper surface. The lamination, after being placed in contact with under surface of the heel, receives the long nails *26* which are driven through counterbores *25* of the sockets, so as to pass through washers *20*, which underlie metal plate *15*, and extend into the shoe heel *10* proper, the heads *21* of these nails being snugly received into the inner ends of tiny sockets *24* of the lamination *12*. This firmly attaches the lamination upon the shoe heel.

Before attaching the lamination, however, to the shoe heel there will be lodged in both the heel and lamination the complementary resilient means which are to serve both as shock-absorbing cushions as well as resilient tread elements for the shoe heel. In Figure 10 there is shown a globular part, being a rubber semispherical body *16* formed with a central semispherical bore *17* therein; in Figure 11 is disclosed a rubber semispherical tread element *19* to cooperate with the cushion shown in Figure 10, which semispherical tread element has an integral central semispherical stub *19a* extending from its base portion. The periphery of the element *19* is formed with downwardly extending radially disposed fins *28*, providing intervening depressions or recesses *19B* which in depth gradually grow wider as the centermost plane ridge *28a* of the tread elements are reached. It is obvious that better traction is had, better antiskid bearing between the shoe and the sidewalk it treads on by formation of the fins and recesses, especially when walking is done on snow, ice, etc. The radius of each rubber cushion *16* is greater than the thickness of the heel *10*, that of tread element *19* is greater than the thickness of lamination *12*.

The semispherical rubber cushions *16* are taken and snugly laid in the cavities *18* of the underside of heel *10* of the shoe so they project with portions *D* beyond the inner side of the heel and have their base portions flush with the other side of heel *10*. The series of rubber tread elements *19* are then taken and the elements are inserted into the recess openings *22* of the lamination *12* in such a manner that their semispherical stubs *19a* will project through corresponding openings *N* formed in the metal plate *15*, into the semispherical bores *17* of the rubber cushions *16*. The base portions of tread elements *19* abut the under side of metal plate *15*. Abutting the upper side of these plates are the base portions of the rubber cushions *16* whereby their peripheral portions *E* project above the upper surface of heel *10*.

Due to the fact that the major radial portions of the tread elements *19* are seated in the recesses *22*, and the minor portions thereof project beyond

the under surface of the lamination *12*, these tread elements cannot work loose and become displaced from these semi-spherical openings. Vulcanization may be resorted to to further hold them in place. After the lamination is attached to the heel, in the manner already explained, it will be seen that the outer terminals of the fin *28* and recessed portions intervening between them will be the parts that will make contact firmly with the surface the shoe wearer is engaging in walking or standing, and in order to enhance and equalize as well as counterbalance the traction imparted to these rubber tread elements and to improve the wearing qualities of the lamination to which they are attached, I form marginally of the lamination so as to skirt these said tread elements a plurality of spaced apart semi-spherical skids *33* which are rounded in shape and formed with similar fins and intervening depressions already noted. All of these semispherical skids, large and small contact the undersurface which is engaged by the heel of the shoe, all at the same time. However, knowing that one side of the heel will ordinarily wear out faster than the other I have multiplied the number of tiny skids *33* on the left side of the heel lamination *12* with relation to the number provided upon the right side thereof, as shown clearly in Figure 2, which also has the effect to steady the even tread of the rubber tread elements so the heel makes contact with the roadway under an even keel most of the time.

In order to reinforce and increase the life of the semispherical rubber tread elements *19* I may provide therefor dish-shaped metal liners *29* formed with base flanges *30* as shown in Figure 5. In mounting these liners, in position, they are seated snugly in the openings *22-23* of the lamination with their base flanges countersunk therein as illustrated in Figure 4. This having been done, semispherical rubber elements *19* will then be seated in them snugly. Whether these elements *19* are seated in the liners or not, it will be seen that at the inner planes of the grooves or depressions intervening between the fins *28* are shoulders *32* disposed in a plane at right angles with respect to their stems *19* these are the points where compressibility of the tread elements causes great dilation of them so the tread elements are crowded against the adjacent surfaces of the openings *22-23* of the lamination; this being the case is the reason why the liners *29* are desirable, which are made of metal and are more sturdy and long-lived than the material from which the lamination itself is made of.

Another way in which the tread elements *19* of semispherical shape may enjoy long life, even when subjected steadily to rough usage is to compose these parts of a series of superimposed rubber rings *P* shown in Figures 4 and 12, these rings have aligning holes *R* in them in which vulcanizing material may be poured hot as a means of homogeneously uniting all of the rings. As shown in Figure 4 these rings are graduated in diameter towards the outer end of the tread element *19* the lowermost ring of least diameter is formed flat as at *S*, the uppermost ring *P1* of largest diameter carries the semispherical stub *19a*. This composite tread element is shown seated in the conical liner *30*.

From the foregoing it is obvious that there is provided a shoe heel adapted to withstand rough usage, severe impacts, and unequal wear. When the nails *26* are driven through the heel *10* into the shoe sole *B*, it presses the heel and this in

turn mashes the protruding ends E of the semi-spherical cushion elements 16 against the shoe sole so here direct resiliency is felt. The shoe wearer equipped with my invention on the heels of the shoe assumes a better posture whether standing or engaged in locomotion because the multiplicity of closely contiguous tiny skids 33 formed on the left side of the heel, cooperating with the relatively larger anti-skid tread elements 19 impart to the heel an equalized, counterbalanced effect resulting in no drag upon any part of the heel which would promote uneven wear, or cause uneven weight to be applied by some of the foot muscles with respect to others, all tending to inconvenience the shoe wearer and entailing faulty posture. Also in walking, should the novel heel encounter ice, snow or irregularities in the pavement or walking surface, the grip of the heel will be firm and steady resilient, because of the grooved rubber constituency of the skids and tread elements. The heel lamination will give yieldably, and the rubber tread elements 19, under pressure of the weight of the wearer's feet, will mash the fins 28, and peripheral upper portions of cushion elements 16, between the fins dirt, packed snow particles and foreign particles that otherwise might become embedded into the rubber elements themselves; and these elements may with some degree of friction also rotate in their heel bearings due to studs 19A being lodged in the rubber cushions in the heel; in pressing back on these tread elements, they dilate in openings 22—23, causing rubber studs 19A to enlarge which squeezes rubber cushions 16, which exert a shock absorbing action on the shoe sole B. Any part of the assembly of coacting rubber and non rubber but pliable material such as leather or composition matter which is relatively thin and separated from adjacent surfaces may effectively be vulcanized so as to fill all voids with cement rubber and otherwise brace these thin spots.

I do not intend to confine myself to the exact details of construction set forth and illustrated herein but intend to cover all variations falling within the purview of the appended claims. For example, the same advantages would attend employing any simple feature of my invention upon a conventional rubber heel or heel of any other construction to increase the wearability and convenience thereof.

What I claim is:

1. A shoe having a heel and a heel lamination of the same contour as the heel and operatively attached thereto overlappingly, a washer interposed between the heel and its lamination, and a plurality of globular rubber tread elements rotatably mounted in said heel and heel lamination and having radiating fins formed thereupon as tread surfaces spaced below said lamination, and means confining said globular elements within said lamination.

2. A shoe having a heel lamination shaped to the same contour of the heel and mounted exteriorly therefor, said lamination being chambered out at spaced apart points across the effective tread area of the lamination to provide a plurality of dish-shaped cavities opening out centrally into the bottom of the lamination, and a plurality of resilient globular tread elements rotatably seated against displacement in said cavities and having radially disposed fins projecting below the lamination that the shoe rests upon.

3. A shoe having a heel and a lamination shaped to the outline of the heel and surmount-

ing its under side, a washer plate counter sunk into said lamination and also contacting said heel, said lamination being formed marginally with a plurality of spaced apart compressible globular tiny elements projecting below its under surface, and a plurality of rubber globular tread elements rotatably anchored into both heel and lamination and having radially disposed fins projecting out of said lamination below its under surface.

4. In combination with a shoe and its heel, a lamination secured to said heel against its under surface, globular rubber elements imbedded into said heel, globular rubber elements having stems extending yieldably in to said first named rubber elements, and having outermost radially extending fins projecting below the lamination and rotatedly confined in the latter.

5. In combination with a shoe and its heel, a lamination of lesser thickness than the heel secured in contact with its under surface, said lamination being formed marginally with a plurality of integral convex tread elements of tiny construction, and being also formed so as to be skirted by said elements with a plurality of globular annular cavities, semispherical rubber cushions confined in said heel, a plurality of semi-globular tread elements having extensions received into the rubber cushions aforesaid yieldably, and a plurality of radially disposed arcuate fins formed integrally upon the last-named semi-globular tread elements seated in said cavities also but projecting terminally below the lamination to the same distance therebelow that the convex elements project therebelow.

6. In combination with a shoe having a heel and a lamination secured thereto, said heel and lamination being formed with a series of complementary spherical cavities, one set of semispherical cavities being formed in the heel and another in the lamination in communicating relationship, semispherical rubber cushions seated in the cavities of the heel and having central bores, globular rubber tread elements seated in the cavities of the lamination and having rod-like stems projecting yieldably into the bores of the cushions, and a series of radially disposed downwardly extending peripheral fins formed upon the lower parts of the globular tread elements and projecting below the lamination to be directly tread upon in service of the shoe.

7. In combination with a shoe heel, a heel lamination having a countersunk washer plate therein contacting the heel, being fastened directly into the heel, means affixing the lamination upon the under surface of the heel, said heel being formed with a plurality of semiglobular cavities having their largest diameters opening out of the under side of the heel, said lamination being formed with a plurality of annular cavities in line with the other cavities having inner large diameters opening out of the upper surface of the lamination and smaller diameters opening out from the under side thereof, semispherical rubber cushions seated snugly in the cavities of the heel flush with its under side, semispherical rubber tread elements of a depth greater than the depth of the lamination cavities seated in the latter with their largest diameters flush with the upper surface of the lamination and their smallest diameters projecting below the under surface thereof, central stems on the tread elements projecting into the centers of the cushion, and means holding the lamination against displacement from said heel.

8. In an article of the kind described, the combination of a sectional heel, a plurality of sectional globular members partly rotatedly encased in each section of the heel, with extensions of one set entered into the other set of rubber members yieldingly, one set of rubber members projecting beyond the sectional heel to be directly tread upon, and means attaching both sections of the heel together.

9. A sectional heel for shoes having a plurality of spherically solid rubber tread elements partially and rotatedly projecting into both sections of the heel, whereby pressure upon one point of all rubber tread elements imparts transmittingly resiliency against the diametrically opposite points thereof within the heel, said tread elements projecting rotatedly beyond the sectional heel, a series of tiny rubber tread skids formed upon one of the sections of the heel extending down to the same level as the projecting portions of said spherically solid rubber elements.

10. In combination with a shoe heel, a lamination thereon having a countersunk recess, a plate seated in said recess flush with its adjacent surface, nails securing said plate to said heel, said lamination being attached to said heel so as to conceal the nails, and a plurality of semi-spherical rubber tread elements having the major radial portion thereof seated in said lamination and a minor portion thereof projecting below the same.

11. In combination with a shoe heel, a lamination secured thereto, a plate counterseated in said lamination contacting said heel, and a plurality of semispherical rubber tread elements having its major radius seated in said lamination with its flat surfaces contacting said plate and having its minor radius projecting below the lamination and formed with a circumferential series of fins.

12. In combination with a shoe heel, a lamina-

tion having a series of semi-spherical cavities formed therein with their larger diameters opening out of its top surface and smaller diameters opening out of the opposite under surface, metal liners mounted in said cavities, and semispherical rubber tread elements having stems anchored into the heel and outer rounded finned surfaces projecting below the lamination, being seated in said liners.

10 13. In combination with a shoe heel a lamination having cylindrical tiny sockets, and a series of semi-spherical openings, said heel formed with semispherical cavities with their larger diameters opening out of its under surface, a plate counterseated in said lamination contacting said heel, nails passing through said plate into said heel and having heads snugly lodged in said tiny sockets, semispherical rubber cushions lodged in said cavities of the heel and having central bores, and semispherical rubber tread elements seated in the semi-spherical openings of the lamination with their lower ends projecting beyond the lamination to form skids, and stems formed upon the tread elements snugly received in the bores of the cushions.

15 14. As a new article of manufacture a heel lamination formed with a series of semi-spherical openings, and with tiny cylindrical sockets having narrow central counterbores opening out of the lamination, and a countersink extending over the effective area of the lamination.
